UNITED STATES PATENT OFFICE.

MARY H. CLARKE, OF FRANKLIN, PENNSYLVANIA.

DESIGN FOR A SET OF CARDS.

48,773.

Specification for Design.

Patented Mar. 28, 1916.

Application filed March 8, 1915. Serial No. 12,993. Term of patent 3½ years.

To all whom it may concern:

Be it known that I, MARY H. CLARKE, a citizen of the United States, residing at Franklin, in the county of Venango and State of Pennsylvania, have invented a new, original, and ornamental Design for a Set of Cards, (for playing a game which I have named "Mother Goose,") of which the following is a specification, reference being had to the accompanying drawings, which form a part thereof.

The drawings show a face view of each of the cards which constitute the set of cards to which my new and original design is applied.

I claim:

The ornamental design for a set of cards as shown and described.

MARY H. CLARKE.

Witnesses:

MILDRED M. SWANEY,
